Primary Examiner — Angela Lee(74) *Attorney, Agent, or Firm* — Michael C. Pophal(57) **CLAIM**

We claim the ornamental design for a wall light device, as shown and described.

DESCRIPTION

FIG. 1 is a front perspective view of the design.

FIG. 2 is a rear perspective view of the design.

FIG. 3 is a front view of the design.

FIG. 4 is a rear view of the design.

FIG. 5 is a right side view of the design.

FIG. 6 is a left side view of the design.

FIG. 7 is a top view of the design; and,

FIG. 8 is a bottom view of the design.

The portions of the wall light device shown in broken lines form no part of the claimed design.
